UNITED STATES PATENT OFFICE.

WILLIAM FRANCIS McMAHON, OF JOHNSTOWN, PENNSYLVANIA.

SIGNAL-LAMP.

1,380,155.

Specification of Letters Patent. Patented May 31, 1921.

Application filed August 27, 1917. Serial No. 188,327.

To all whom it may concern:

Be it known that I, WILLIAM F. McMAHON, a citizen of the United States, residing at Johnstown, in the county of Cambria and State of Pennsylvania, have invented certain new and useful Improvements in Signal-Lamps, of which the following is a specification.

This invention relates to improvements in lamps of the type used for signal or display purposes on automobiles. The invention consists in the combination and arrangement of parts to be hereinafter fully described, pointed out in the appended claim and illustrated in the accompanying drawing which forms a part of this specification and in which—

Figure 1 is a front view of the lamp.

Fig. 2 is a section through the lamp on line 2—2 of Fig. 1.

Fig. 3 is a sectional view of the automobile steering post showing the control switch for the lamp which is applied thereto.

Fig. 4 is a diagrammatic view showing the lights and the electric control therefor.

Like reference characters denote corresponding parts throughout the several views.

Upon a bracket arm 1 which may be suitably secured to the front or rear of the vehicle in a conspicuous position I secure a casing comprising the cylindrical member 2 and back 3. To the front end 4 of the casing the door 5 is hinged and provided with the glass face 6. The outer surface of the face 6 is painted or otherwise rendered opaque except for three small circular portions 7, 8, 9 which are left transparent and in which portions the letters "S," "L," and "R," respectively, are displayed, said letters representing the words "straight," "left" and "right." Within the casing 2, I provide a diaphragm 10 in which three electric lights 11 are fixed, said lights each being provided with a reflector 12. Each light, further, is incased in a substantially cylindrical housing 13 which also encircles the reflector of that light and extends from the diaphragm to the glass face 6 and encompasses one of the transparent portions 7, 8 or 9 of that face. The casing 2 is formed with an aperture 14 in alignment with an aperture 15 in one of the housings 13, each housing being provided with a similar aperture, so that a person may see

from a position at one side of the casing 2 whether any of the lights are lighted. Each housing 13 at the end abutting the face 6 is provided with a flexible band 16 which tends to prevent the spread of light over said face beyond the confines of that housing-end.

The reflectors 12 are in the form of collars secured to the housings 13 and have flanges secured to the diaphragm 10. 65

A flexible tube 17 secured to the back 3 of the casing carries the electric light wires to the steering post 18 and through the same to the switch 19 secured to said post. The switch 19 is provided with three keys 20 70 each of which controls one light 11. When the driver is about to turn to the right he presses the key 20 that will turn on the light 11 that will illuminate the transparent face portion 9 whereon the symbol "R" is displayed. In like manner he will control the illumination of the other transparent face portions. The driver, from his seat, may at all times know whether the lights are in working order through the medium of the 75 apertures in the casing and housings 13.

What is claimed is:—

A signal lamp including a frusto-conical casing, a back at the smaller end of said casing, a diaphragm held by the back, electric light bulbs carried by said diaphragm and arranged in triangular relation, flaring housings within said casing having their smaller ends fitted over said bulbs and abutting against said diaphragm, collars received within the smaller ends of the housings and secured thereto, said collars having flanges secured to the diaphragm, a transparency at the larger end of said casing lying against the large ends of said 90 flared housings and made opaque except at areas defined by the larger ends of the housings with signal indicia on such areas, bands around the flared ends of the housings, said casing and housings having registering apertures at the sides thereof, and means for selectively lighting said electric bulbs. 95

In testimony that I claim the foregoing as my own I have hereto affixed my signature in the presence of two subscribing witnesses. 105

WILLIAM FRANCIS McMAHON.
